[57] **CLAIM**

The ornamental design for the design of an exit alarm lock, as shown and described.

DESCRIPTION

FIG. 1 is a perspective view of an exit alarm lock showing our new design;

FIG. 2 is a front view of a design of exit alarm lock according to the present invention, the rear being unornamented;

FIG. 3 is a bottom view of a design of exit alarm lock according to the present invention;

FIG. 4 is a top view of a design of exit alarm lock according to the present invention;

FIG. 5 is a left side view of a design of exit alarm lock according to the present invention; and,

FIG. 6 is a right side view of a design of exit alarm lock according to the present invention.

The broken line disclosure is for illustrative purposes only and forms no part of the claimed design.
